UNITED STATES PATENT OFFICE.

FRED AICHINGER, OF CLEVELAND, AND JOSEPH J. KOPACKA, OF EAST CLEVELAND, OHIO.

DESIGN FOR A BOTTLE.

Application filed June 28, 1928. Serial No. 27,313. Term of patent 14 years.

To all whom it may concern:

Be it known that we, FRED AICHINGER and JOSEPH J. KOPACKA, citizens of the Republic of Germany and the United States, respectively, and residents of Cleveland, in the county of Cuyahoga and State of Ohio, and of East Cleveland, in the county of Cuyahoga and State of Ohio, have invented a new, original, and ornamental Design for a Bottle, of which the following is a specification, reference being had to the accompanying drawing, forming part thereof.

Figure 1 is an elevation of a bottle, showing out new design. Figure 2 is a sectional view on the line 2—2.

We claim:

The ornamental design for a bottle, as shown.

FRED AICHINGER.
JOSEPH J. KOPACKA.
